1,028,248. MEANS FOR SECURING
RAILS TO METAL TIES. WILLIAM
HENRY MORGAN, Alliance, Ohio. Filed
Sept. 12, 1911. Serial No. 648,997.

To all whom it may concern:

Be it known that I, WILLIAM H. MORGAN, a citizen of the United States, residing at Alliance, in the county of Stark and State of Ohio, have invented certain new and useful Improvements in Means for Securing Rails to Metal Ties; and I do hereby declare the following to be a full, clear, and exact description of the invention, such as will enable others skilled in the art to which it appertains to make and use the same.

My invention relates to an improvement in means for securing rails to metal ties, the principal object being to dispense with the use of bolts or other parts passing through holes or recesses in the ties or rails.

A further object is to produce simple means whereby the rail may be released and readjusted to compensate for wear.

With these and other objects in view my invention consists in a chair seated on the tie and adapted to receive the rail, interchangeable rail clamping plates seated on the chair and held against lateral and endwise movement thereon, and spring clamps for locking the parts together.

My invention further consists in the parts and combinations of parts as will be more fully described and pointed out in the claims.

In the accompanying drawings, Figure 1 is a view in perspective showing a section of a rail in elevation and the tie in section. Fig. 2 is a view in perspective of a section of a tie and showing the chair, insulation, clamping plate and armor plates. Fig. 3 is a view in section longitudinally of the tie and transversely of the rail showing the clamping plates in one adjustment. Fig. 4 is a similar view showing the clamping plates changed and the rail shifted to compensate for wear, and Fig. 5 is a view in section through the tie, chair, and clamps showing means for preventing movement of the chair or the tie. The tie 1 is preferably I-shape in cross section, its base flange 2 being wider than its top flange 3.

4 are the chairs of greater length than the width of a rail, and wider than the tie on which it is seated. Each chair is provided at its side edges with the depending side flanges 5, adapted to overhang the opposite sides of the tie as clearly shown in Fig. 2, and also at its opposite ends with the upwardly projecting flanges 6, the space intermediate the inner ends of the top flanges 6, being greater than the width of the base flange of the rail so as to receive the latter between them and permit it to rest solidly

on the top surface of the chair as shown in Figs. 3 and 4.

7 is insulating material molded or pressed into shape and covering the upper flange 3 of the tie, and 8 are the ribbed armor plates bearing against the insulation at the underside of the top flange 3 and forming bearings for the spring clamps 9, substantially as shown in my pending application No. 643,418, filed August 10th, 1911.

10 are the clamping plates adapted to rest on the chair intermediate the top flanges 6. Both plates are provided with lips 11 adapted to overlap the base flange of the rail at the opposite sides thereof, and one is provided with the laterally projecting shoulders 10^a and the other with similar shoulders 10^b. These shoulders are adapted to bear against the inner or adjacent ends of the flanges 6, and are alike except that shoulders 10^a are narrower than shoulders 10^b for a purpose that will be hereinafter described.

The parts are so constructed and proportioned, that when the clamping plates are in place on the chair, there will just be room sufficient between the inner or adjacent ends of the plates for the base flange of the rail, so that the latter will be overlapped by the lips. When the parts are thus applied, it will be seen that there can be no lateral movement of the chair 4 on the tie, or any longitudinal or lateral movement of the clamping plates, hence when the parts are secured together by the spring clamps 9 the rail will be solidly locked to the tie.

The spring clamps 9 each consist of an upper jaw terminating in an upwardly curved free end, and a lower jaw terminating in an upwardly curved free end, and are of a size sufficient to rest clear of the chair and tie. The flanges 6 are shallower than the thickness of the clamping plates 10, so that the clamps pass over the same without contacting therewith, and bear directly on the top faces of the clamping plates 10. These clamps 9 are preferably made of hard tough and finely grained steel, of a size sufficient to hold the rails to their seats and to withstand the strain and shocks to which they are subjected, and are under tension when applied. They may be inserted and driven on endwise the chair, or they may be sprung on, and when in place, the jaws lap the clamping plates and top flange of the tie and hold all the parts solidly together.

In assembling the parts, the clamping plates with the thicker shoulders 10^b are placed to the inner side of the rail as shown in Fig. 3. After the rail has worn sufficiently to require regaging of the tracks, the clamping plates may be reversed as shown in Fig. 4, thus shifting the rail to the left, or toward its companion rail, a distance equal to the difference in width of the shoul-

ders 10^a and 10^b. After the rail has worn on one side it may be turned end for end, thus presenting the unused side to the wheel flanges. If desired the top of the tie may be recessed as at 14 and the chair provided with an upset projection 15 adapted to enter said recess to prevent any endwise movement of the chair on the tie, the recess being sufficiently large to permit the insulating material to fully cover and protect the projection. With my improvement the chairs rest on the top of the tie, and the parts are all secured together by spring clamps, hence the improvement can be produced at much less cost than those wherein seats are provided for the chairs and holes or other openings formed for bolts or other securing devices.

It is evident that many slight changes might be resorted to in the relative arrangement of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:-

1. The combination with a metal tie having a top flange, of a chair seated on said flange and provided with a pair of upwardly projecting side shoulders near each end, clamping plates resting on the chairs and provided with shoulders engaging a pair of the shoulders on the chair and each also provided with a lip adapted to overlap the base flange of the rail, and means for locking the plates, chair and tie together.

2. The combination with a metal tie having a top flange, of a chair having a pair of upwardly projecting flanges at each end, with a space between the two pairs for the base flange of the rail, two clamping plates adapted to rest between said flanges and each having laterally projecting shoulders to engage the inner ends of said flanges, and a lip to overlap the base flange of the rail, and means for locking the plates, chair and tie together.

3. The combination with a metal tie having a top flange, of a chair having depending flanges to overhang the sides of the top flange of the tie, and a pair of upwardly projecting flanges near each end, clamping plates, each having laterally projecting shoulders to engage the inner ends of said upwardly projecting shoulders, and a lip to engage the base flange of the rail and means for securing the plates, chair and tie together.

4. The combination with a tie, of a chair having shoulders arranged in pairs on its

upper surface, and two clamping plates each having a lip to engage the base flange of the rail and laterally projecting shoulders to engage the shoulders on the chair, the shoulders on one plate being wider than the shoulders on its companion plate.

5. The combination with a tie, of a chair having a pair of upwardly projecting flanges near each end, and two interchangeable clamping plates, each having a lip to overlap the base flange of the rail, and each having laterally projecting shoulders to engage the inner ends of the upwardly projecting flanges on the chair, the shoulders on one clamping plate being wider than the shoulders on its companion plate.

6. The combination with a metal tie having a top flange, of a plate having a depending flange at each side to overhang the top flange of the tie, and a pair of upwardly projecting parallel flanges at the sides and near each end, and two interchangeable clamping plates each having a lip to overlap the base flange of the rail and each having laterally projecting shoulders to engage the inner ends of the upwardly projecting flanges on the chair, the shoulders on one clamping plate being wider than the shoulders on its companion plate.

In testimony whereof, I have signed this specification in the presence of two subscribing witnesses.

WILLIAM HENRY MORGAN.
